UNITED STATES PATENT OFFICE.

BURTON P. FLORY, OF PLAINFIELD, NEW JERSEY.

COUPLING CARRY-IRON.

No. 926,477.

Specification of Letters Patent.

Patented June 29, 1909.

Application filed May 20, 1908. Serial No. 433,908.

To all whom it may concern:

Be it known that I, BURTON P. FLORY, a citizen of the United States, residing at Plainfield, in the county of Union and State of New Jersey, have invented a new and useful Improvement in Coupler Carry-Irons, of which the following is a specification.

My invention relates to the carry-iron or support for the coupler shank or draw-bar of a railroad car or locomotive engine draft-gear, and has for its object to prevent loosening and play of the carry-iron, to maintain the coupler at its normal height from the rails, and to facilitate the disconnection of the carry-iron when desired to drop the coupler.

Ordinarily, the coupler carry-iron consists of a rolled or wrought iron bar spanning the draft-timbers, or equivalent members formed on the dead-block or end sill of a locomotive engine or railroad car, and secured thereto by vertically arranged bolts the nuts of which constantly work loose and thereby cause play of the carry-iron and lowering of the coupler, considerable time being also lost in disconnecting the nuts from the bolts for removing the carry-iron when desired to drop the coupler draw-bar.

The invention consists in features of novelty as hereinafter described and claimed, reference being had to the accompanying drawing forming part of this specification, whereon,

Figure 1, is a front elevation of a metallic dead-block adapted to be fixed to the end sill of a car wood underframe, and having my improved coupler draw-bar carry-iron applied thereto on its underside; Fig. 2, a vertical transverse section thereof on line 2, 2, in Fig. 1; Fig. 3, a horizontal section through the dead-block and carry-iron on line 3, 3, in Fig. 1; Fig. 4, an end view thereof, and Figs. 5 and 6, corresponding views to Figs. 1 and 2, showing a modification of the improvement.

Like letters and numerals of reference denote like parts in all the figures.

Referring to Figs. 1, 2, 3, and 4, a represents a preferable form of my improved carry-iron which may be of any suitable shape and composed of cast steel, wrought iron, or other suitable metal, the carry-iron *a* in the present case being channel-shaped in cross section except at the ends where it is attached to the dead-block *b* as hereinafter more particularly described. Transversely through the dead-block *b* in its underside (or

between the said end members as the case may be) is the usual opening 1 for the passage and play therethrough of the coupler-shank or draw-bar *c*, the horizontal channel-shaped portion 2 of the carry-iron *a* on which the draw-bar *c* is supported and rides, spanning the opening 1 at the bottom transversely to the draw-bar *c*, and formed preferably at each end beyond the corresponding side wall 3 of the opening 1 with an upwardly extending lug or ear 2' which is preferably solid, the lug 2' at one end of the carry-iron *a* being preferably formed with two opposite side circular trunnions 4 which on assembling the parts are mounted pivotally or hingewise in concave (preferably semi-circular) bearings 4' formed horizontally on the inside of two opposite upright webs 5 which project from the dead-block *b* (or other said end members) and with the corresponding side wall 3 of the opening 1 form a pocket *d* for the lug 2', while the lug 2' at the other end of the carry-iron *a* is secured within a similar pocket *d'* formed by the upright webs 5' and the corresponding side wall 3 of the opening 1, by a pin or bolt 6 which is passed horizontally through the brackets or sides 5 of the pocket *d* and lug 2', and held in place by a cotter pin (or nut) 7, it being here noted that in the above described assembling and attachment of the carry-iron *a* to the dead-block *b* (or other said end member) the inner faces of the lugs 2' are adapted preferably, to bear against the rear sides of the walls 3 of the opening 1 (or against the corresponding walls connecting the sides 5, 5', of the pockets *d*, *d'*), whereby longitudinal play of the carry-iron *a* and shear stress on the trunnions 4 and pin 6 due to the lateral movement of the draw-bar *c*, are prevented.

In the above construction, by securing the carry-iron *a* to the dead-block *b* (or other said end member) at one end by the hinge 4 and at the other end by the removable pin or bolt 6, arranged respectively, horizontally, or in a plane parallel to the bearing surface of the carry-iron *a* instead of by bolts at right angles to the said surface, combined with the facial engagement of the lugs 2' with the side walls 3 of the opening 1 (or corresponding walls of the pockets *d*, *d'*) forming parts of the member to which the carry-iron *a* is attached, the latter is firmly held longitudinally and lowering thereof due to the loosening of the nuts on the ordinary bolts, prevented; moreover, by removing the pin 6 the

carry-iron *a* is readily and quickly disconnected or uncoupled thereat and can be swung downward about its hinged lug *2'* clear of the opening *1* and the draw-bar *c* dropped when desired without the necessity of loosening and removing the nuts of the ordinary bolts.

I do not limit myself to forming the carry-iron *a* with upwardly projecting lugs *2'*, as it is obvious that the same result can be obtained by forming the end portions of the carry-iron *a* in any suitable manner adapted for their horizontal pivotal connection within the pockets *d*, and *d'*.

15 In the modification of my invention seen in Figs. 5 and 6, each lug *2'* of the carry-iron *a* is attached to the dead-block *b'* by a removable horizontally arranged pin or bolt *6'* instead of by a hinge *4* at one end and by a removable pin *6* at the other end as previously described; and the dead-block *b'* adapted to be fixed to a metallic instead of a wood end sill.

What I claim as my invention and desire to secure by Letters Patent is:—

25 1. The combination with the coupler draw-bar of a car draft-gear and a suitable end member of the car underframe, of a carry-iron arranged transversely to and adapted to support the said bar, a lug projecting from the carry-iron at or adjacent to each end thereof, a pocket adapted to receive

the said lug and forming part of the said member, a trunnion projecting horizontally from one of the said lugs at right angles to the longitudinal center of the carry-iron, a 35 suitable bearing for the trunnion within the corresponding pocket, and a pin adapted to be passed horizontally through and to fit the other said lug and sides of its corresponding pocket at right angles to the said center, substantially as described. 40

2. The combination with the coupler draw-bar of a car draft-gear and the dead-block of the car underframe, of a carry-iron arranged transversely to and adapted to support the said bar, two opposite upright webs forming parts of the dead-block at each side of the draw-bar opening therethrough, a lug projecting from the carry-iron between the said webs, trunnions projecting horizontally from one of the said lugs at right angles to the longitudinal center of the carry-iron, suitable bearings for the trunnions on the inside of the corresponding webs, and a pin adapted to be passed horizontally through and to fit the other said lug and webs at right angles to the said center, substantially as described. 45 50 55
